UNITED STATES PATENT OFFICE

OSCAR C. KAVLE, OF SYRACUSE, NEW YORK, ASSIGNOR TO HARVEY A. MOYER, OF SYRACUSE, NEW YORK.

PAPER-FEED MECHANISM FOR TYPE-WRITING MACHINES.

1,033,415.

Specification of Letters Patent.

Patented July 23, 1912.

Application filed August 3, 1908. Serial No. 446,578.

To all whom it may concern:

Be it known that I, OSCAR C. KAVLE, a citizen of the United States, residing at Syracuse, in the county of Onondaga and State of New York, have invented a new and useful Improvement in Paper-Feed Mechanisms for Type-Writing Machines, of which the following is a specification.

This invention relates more particularly to improvements in paper feeding and guiding mechanism for typewriting machines.

The objects of the invention are to produce an efficient mechanism of simple and inexpensive construction in which the feed or presser rolls automatically adjust themselves to different thicknesses of paper and papers which are not of uniform thickness, and insure the proper feeding of the paper; also to construct the mechanism so that it can be applied with but slight change to carriages of different lengths; also to make the mechanism largely of sheet metal and wire parts to reduce the weight and cost thereof; also to support the feed rolls by a flexible frame composed in part by the paper guides; also to provide a paper feed table with simple and inexpensive means for attaching it to the carriage; and to improve paper feed mechanisms for typewriters and analogous machines in the respects hereinafter described and set forth in the claims.

In the accompanying drawings, consisting of two sheets: Figure 1 is a front elevation, partly broken away, of a typewriter carriage provided with paper feed and guide means embodying the invention. Fig. 2 is a plan view, partly in section, thereof. Fig. 3 is a sectional plan view thereof in line 3—3, Fig. 5. Fig. 4 is an end elevation thereof. Figs. 5 and 6 are transverse sectional elevations thereof in lines 5—5 and 6—6, respectively, Fig. 1. Fig. 7 is a fragmentary perspective view of adjacent guides.

Like letters of reference refer to like parts in the several figures.

A represents the platen which is removably journaled in a carriage, consisting of end plates B connected by a casting b and a scale bar b'. The construction of the carriage and means for removably securing the platen therein are substantially as dis-

closed in my prior application, Serial No. 311,756, filed April 14, 1906.

C represents sheet metal paper guides which are secured at their rear ends, by screws d, or other fastenings, to upright lugs d', on the carriage, and curve downwardly, forwardly and upwardly under the platen with their free front ends close to the platen. The forward portions of the paper guides are connected by two slender horizontal rods or wires E and F which pass through holes in down-turned lugs e and f formed on the guides. The wires E and F are loose in the lugs e and f but they extend nearly from one end plate of the carriage to the other, and the plates prevent displacement of the wires. The wires E and F are of spring temper, and the sheet metal guides and wires form an exceedingly light and flexible frame that can yield bodily at its front and can also be flexed at any part of its length.

G and H represent respectively front and rear, or delivery and receiving paper feed or pressure rolls. The front rolls are journaled on the wire E between the paper guides. The rear rolls are journaled on separate short shafts i, Figs. 2 and 5, removably seated in open slots i', in the forked rear ends of auxiliary sheet metal paper guides or roll supports I which are arranged between the guides C and are pivoted by down-turned perforated lugs i² at their front ends on the wire F. The rolls H could be suitably journaled on pivoted supports I of other construction.

Ordinary rubber-covered wooden rolls are employed and the rear rolls have the usual metal sleeves bearing on the shafts i, but the front rolls, see Fig. 2, preferably have short bushings h in their ends that bear on the wire E and leave enlarged openings in the rolls between the bushings. The object of this construction is to enable the wire E to flex slightly inside of the front rolls as well as between them without creating friction in the bearings.

K, Figs. 2, 3 and 5, represents a rock shaft which is seated at its ends in bearings in the carriage end-plates and rests in seats in the carriage lugs d' beneath the rear ends of the paper guides, which prevents the shaft from springing between its ends.

Arms *k* rigidly secured to the rock shaft *K* and projecting forwardly therefrom under the paper guides *C* are connected at their forward ends by a spring rod or wire *k'*. This rod extends horizontally beneath the guides *C* and *I* and normally bears against the auxiliary guides *I*, which are arranged slightly lower than the other guides *C*. The rod *k'* is pressed upwardly by suitable means, such as springs *L* surrounding the ends of the rock shaft, and holds the rear rolls *H* yieldingly against the platen. As the engagement of the rear rolls with the platen limits the upward swing of the auxiliary guides, the upward pressure of the rod *k'* thereon, acting through the connecting wires *F*, also presses the front ends of the paper guides *C* upwardly and holds the front rolls *G* yieldingly against the platen.

An arm or handle *M*, Figs. 1, 2 and 4, is secured to one end of the rock shaft for rocking it to allow the feed rolls to move away from the platen. The paper guides have a normal tendency to spring away from the platen, and whenever the forward end of the lever *M* is depressed, the guides swing the front rolls away from the platen, and the pressure of the rod *k'* on the auxiliary guides being relieved, the rear rolls fall away from the platen by their own weight, thus freeing the paper on the platen and permitting it to be shifted as may be desired.

N, Figs. 2 and 4, represents spring-adjusting levers having hollow hubs seated in holes in the carriage end-plates and in which the ends of the rock shaft *K* bear. Each spring *L* for the rock shaft is secured at one end to the rock shaft and at the other end to the hub of the adjacent adjusting lever *N*, see Fig. 2. Securing screws *n* passing through slots *n'* in the adjusting levers concentric with the rock shaft in the ends of the carriage, permit the levers to be adjusted to tension the springs *L* as may be desired. By having a spring *L* at each end of the rock shaft the pressure of the rod *k'* at both ends is practically the same, and this result cannot be obtained with a single spring at one end of the shaft unless a shaft of undue size is used, owing to the tendency of the shaft to twist.

The rock shaft and connected wire *k'* constructed and operated as described produces a desirable flexible rocking pressure frame or device for the feed rolls, but other pressure means could be employed.

In a carriage of ordinary length, such as shown in the drawings, four paper guides *C* with three auxiliary guides and three pairs of tandem feed rolls between them are employed. For a shorter carriage, one less guide *C* and pair of rolls with the corresponding auxiliary guide *I* are used, and for longer carriages one or more pairs of rolls with the corresponding guides *C* and *I* are employed. No other change is required to adapt the feed mechanism to carriages of different lengths except to make the wires *E* and *F* and the rock shaft *K* with its pressure rod *k'* of suitable length. The guides *C* lead the paper from the lower edge of the feed table, hereinafter described, to the rear rolls *H* without the aid of the auxiliary guides *I*, but when the advance edge of the paper passes the rear rolls, from which point it should begin to curve around the platen, the auxiliary guides assist in guiding the paper and insure its being properly presented to the front rolls. The pressure rod *k'* yields enough to allow first the rear rolls and then the front rolls to be forced away from the platen by the advance edge of the paper when inserting the sheets, and if sheets of uneven thickness, such as are folded at one edge, or have central recording strips, are used, either roll or either pair of rolls can yield as much as required, independently of the other rolls, on account of the flexible nature of the feed roll support and pressure device. But all of the rolls are held parallel with the platen at all times so as to feed the paper straight, regardless of whether it is of uniform thickness. The platen can be removed from the carriage, leaving the feed mechanism all in place, and when the rolls require to be renewed, the rear rolls with their shaft can be simply lifted out of the bearing slots, and by raising the front rolls until their axle wire *E* is opposite a hole *O*, Fig. 4, in the end of the carriage, the wire can be slipped endwise through said hole to release any or all of the front rolls. After replacing the rolls the wire *E* is shoved back into place, and when the platen is again placed in the carriage it will hold the front rolls down with the axle wire *E* therefore below the hole *O* so that the wire will be retained in place by the ends of the carriage.

As the seven guides are composed of sheet metal stampings in two patterns and are connected by wires, the roll supporting frame is inexpensive to make and the parts can be easily assembled, and as feed rolls just alike are used for carriages of all lengths there can be no confusion in applying the mechanism to different carriages, or in ordering rolls for repairs.

P represents a paper feed table or shelf arranged, as usual, to extend upwardly and rearwardly from the rear ends of the paper guides. The table may be of any suitable construction, but preferably consists of a piece of sheet metal formed with supporting portions at its lower edge separated by slots or openings *p* through which the rear ends of the paper guides *C* extend for attachment.

to the carriage. The supporting portions are bent to form spring clips p' which embrace the rock shaft K between the paper guides, and depending legs p^2 between the 5 clips which bear against the back of the carriage and prevent the table from falling backwardly. The table is thus detachably secured in place on the carriage by integral portions thereof without separate fastening 10 devices, and it can be readily applied and removed. The table can also be tilted forwardly to afford access to parts of the machine (not shown) that are located under it. The feed table thus constructed is adapted 15 for use with other feed mechanisms.

The rolls shown are all of the same length, but if preferred, long central rolls and short end rolls could be employed. The construction of the roll supporting structure consisting 20 of the main and auxiliary guides, or roll supports, and the means for yieldingly holding the rolls to the platen can also be modified without departing from the invention. The feed roll mechanism is also applicable 25 to adding and other machines analogous to typewriters.

I claim as my invention:

1. In a paper feed mechanism, the combination of a rotary platen, a series of independently yieldable paper guides secured and supported at one end, connections between and supported by the movable ends of the guides, and one or more feed rolls mounted on said connections, substantially as set 35 forth.

2. In a paper feed mechanism, the combination of a rotary platen, a series of independently yieldable paper guides rigidly supported in rear of the platen, connections 40 between the guides, and one or more feed rolls mounted on said connections, substantially as set forth.

3. In a paper feed mechanism, the combination of a rotary platen, a series of flexible 45 paper guides, a flexible connection between the guides and supported thereby, and one or more feed rolls mounted on said connection, substantially as set forth.

4. In a paper feed mechanism, the combination of a rotary platen, a series of independent flexible paper guides, a flexible connection common to the whole series of guides and supported thereby, and a series of feed 55 rolls mounted on said common connection, substantially as set forth.

5. In a paper feed mechanism, the combination of a carriage, a rotary platen, a series of independent flexible paper guides attached at one end to the carriage, a flexible connection between said guides remote from the attached ends thereof, and a series of feed rolls mounted on said connection, substantially as set forth.

6. In a paper feed mechanism, the combination of a rotary platen, independently

yieldable main paper guides, an auxiliary paper guide arranged between and supported by said main guides, and feed rolls supported by said main and auxiliary guides, substantially as set forth.

7. In a paper feed mechanism, the combination of a carriage, a rotary platen, independently yieldable main paper guides attached at one end to the carriage, an auxiliary paper guide arranged between said main guides and connected to the free ends thereof, feed rolls supported by the free ends of said main and auxiliary guides, and means for pressing said rolls against the platen, substantially as set forth.

8. In a paper feed mechanism, the combination of a rotary platen, a series of independently yieldable paper guides, a series of feed rolls arranged between the guides and supported thereby, a series of auxiliary paper guides arranged between said guides and connected thereto, and a series of feed rolls journaled on said auxiliary guides between the main guides, substantially as set forth.

9. In a paper feed mechanism, the combination of a carriage, a rotary platen, independently yieldable paper guides attached at one end to the carriage, a roll support arranged between said guides and connected to the free ends of said guides and extending toward the attached ends thereof, feed rolls supported by the free ends of said guides and roll supports, said rolls being pressed yieldingly against the platen, substantially as set forth.

10. In a paper feed mechanism, the combination of a carriage, a platen, independently yieldable paper guides attached at one end to the carriage, a flexible rod connecting the free ends of said guides, a feed roll journaled on said rod, a roll support arranged between said guides and connected to the free ends of said guides and extending toward the attached ends thereof, a feed roll journaled at the free end of said roll support, and means for pressing said last mentioned feed roll against the platen, substantially as set forth.

11. In a paper feed mechanism, the combination of a carriage, a platen, a series of flexible main paper guides attached at their rear ends to the carriage, a flexible rod connecting the front ends of said guides, a series of auxiliary guides arranged between said main guides and pivoted to the front ends thereof, feed rolls supported by the front ends of said main guides and the rear ends of said auxiliary guides, and means for pressing said feed rolls against the platen, substantially as set forth.

12. In a paper feed mechanism, the combination of a carriage, a rotary platen, a series of feed rolls, and a supporting frame for the rolls consisting of a series of flexible sheet metal parts adapted to yield inde-

pendently and a connecting flexible wire, substantially as set forth.

13. In a paper feed mechanism, the combination of a carriage, a rotary platen, a series of receiving feed rolls, a series of delivery feed rolls, a series of flexible paper guides, flexible wires connecting both series of rolls to the flexible guides, and means for holding all of said rolls yieldingly against the platen, substantially as set forth.

14. In a paper feed mechanism, the combination of a carriage, a rotary platen, two series of feed rolls, one arranged in rear of the other, and a supporting frame for both series of rolls consisting of a series of flexible paper guides, a series of yielding supports for one series of rolls, and flexible wires connecting the paper guides and also connecting the two series of rolls to said guides, substantially as set forth.

15. In a paper feed mechanism, the combination of a carriage, a rotary platen, a series of pairs of feed rolls arranged in tandem, and a flexible frame which forms the entire support for the rolls and consists of a series of sheet metal parts of two different forms, and connecting wires, substantially as set forth.

16. In a paper feed mechanism, the combination of a carriage, a rotary platen, a series of independently yieldable paper guides attached at one end to the carriage, two flexible wires connecting the free ends of said guides, a series of feed rolls journaled between said guides on one of said wires, roll supports mounted between said guides on said other wire, feed rolls journaled on said supports, and means for pressing said feed rolls against the platen, substantially as set forth.

17. In a paper feed mechanism, the combination of a carriage, a rotary platen, two series of feed rolls arranged in two different lines, and two sets of paper guides arranged alternately and forming a substantially continuous guide between the two series of rolls, one set of guides supporting one series of

rolls and the other set of guides supporting the other series of rolls, substantially as set forth.

18. In a paper feed mechanism, the combination of a carriage, a rotary platen, a feed roll, a spring support for the roll which tends to move the roll away from the platen, and means acting normally to overcome the spring pressure of said support and force the roll yieldingly against the platen, substantially as set forth.

19. In a paper feed mechanism, the combination of a carriage, a rotary platen, a series of independent pairs of feed rolls, a flexible supporting frame for the rolls which allows any roll to yield independently of the other rolls, and an independent releasable spring-pressed device which normally actuates the flexible frame to hold all of the rolls yieldingly against the platen, substantially as set forth.

20. In a paper feed mechanism, the combination of a carriage, a rotary platen, a series of independently yieldable pairs of feed rolls, a flexible frame for the rolls, an independent flexible spring-pressed device which holds all of the rolls against the platen with a yielding pressure, and means for manually releasing said spring-pressed means, substantially as set forth.

21. In a paper feed mechanism, the combination of a carriage, a rotary platen, a series of pairs of feed rolls, a flexible supporting frame for said rolls, one roll of each pair being mounted on the flexible frame, a separate part yieldably connected to the flexible frame on which the other roll of each pair is mounted, and means acting on said separate part to press all of the rolls yieldingly against the platen, substantially as set forth.

Witness my hand, this 30th day of July, 1908.

OSCAR C. KAVLE.
